MEANS FOR SPACING AND FORMING BUTTONHOLES AND OTHER STITCHINGS IN ARTICLES OF CLOTHING

George Jessop, Ingle Nook, Gomersal, near Leeds, England

Application March 19, 1938, Serial No. 196,884
In Great Britain March 24, 1937

3 Claims. (Cl. 112—65)

This invention relates to an improved means for spacing and forming buttonholes and other stitchings in articles of clothing, and is particularly applicable to the spacing and stitching of buttonholes in vests or waistcoats of men's clothing. It is, however, equally applicable to the sewing on of spaced buttons, bar tackings of sewn buttonholes and other like spaced stitchings. The primary object of the present invention is not only to instantly and accurately indicate the position for each buttonhole, button or other stitchings, but also to allow for the automatic making or stitching of a plurality of separate spaced stitchings along the edge of the garment after the machine has been set.

The present invention comprises in combination with an automatic buttonhole sewing machine of known type in which the work is held stationary and the relative movement of the parts to sew about the buttonhole is produced by travel of the stitch frame including the sewing head of the machine as described for instance in United States Patents Nos. 488,028, 494,280, 655,637 and 713,764, mechanism attachable to said machine comprising means for holding the work and automatically spacing at one operation the position and number of stitchings necessary to fill up an allotted space, and means for automatically stitching successively a plurality of separate stitchings at a pre-determined distance apart at one operation of the machine, i. e., after the machine is once started and before it is automatically stopped.

One embodiment of this invention comprises a gauge adapted to be held in relation to an automatic sewing machine of the "Reece" type such as is described in United States Patents Nos. 488,028, 494,280, 655,637 and 713,764, the said gauge consisting of a plurality of indicating fingers or bars held movably parallel, and mechanism for equally and automatically spacing them apart, means for carrying the gauge in a slidable manner transversely in relation to the head of the sewing machine, clamping means for holding the edge of the garment to be operated upon beneath the needle bar of the machine, and locking the gauge after adjustment, means for automatically sliding the gauge and with it the garment after each separate stitching is completed, and means carried by the gauge co-acting with the starting and stopping gear of the machine whereby the machine after being started is kept in operation and stopped only on completion of the required number of separate stitchings.

This invention will be now more particularly

described making reference to the accompanying drawing in which is shown an embodiment of this invention applicable to an automatic button-hole sewing machine of the reciprocating head type in which the needle bar is moved along the length of the buttonhole whilst the garment is held stationary during the stitching, as described, for instance, in the patent specification of United States Patents Nos. 488,028, 494,280, 655,637 and 713,764.

Fig. 1 is a broken view in plan of one constructional form of the invention.

Fig. 2 is a view in section looking in the direction of the arrow, on line A—A of Fig. 1.

Fig. 3 is a similar view in section on line B—B of Fig. 1.

Fig. 4 is an enlarged detail view in plan.

Throughout the views similar parts are designated by like figures of reference.

The gauge, by way of example, comprises a plurality—say six for instance—of bars or indicating fingers 1, 2, 3, 4, 5 and 6, held movably parallel by links 7. The links 7 are pivoted together at 8 in the centre of their length and at their ends, with the exception of the end links. The extremities of the links 7 are also pivoted to the bars 1—6 at 9 and 9a, the pivots of the latter working in slots in said bars, the whole arrangement constituting a lazy tongs mechanism, so that on moving the bars, each bar will be moved equally apart from its adjacent one.

A gauge so constituted is carried in a slidable manner on a pair of horizontally and parallelly arranged rods 10 fixed parallel with the front edge and transversely in respect of the oscillating head 11 of a sewing machine of the "Reece" type above referred to, by means of eye bolts or sleeves 9b carried on the underside on the bars 1—6.

The rods 10 are carried in angular relation to the table of the sewing machine by end frames or brackets 12 adapted to be attached to the edge of a table carrying the sewing machine, so that the rear edges of the bars 1—6 will be adjacent to the surface of the usual table 11a of the machine, but clear of the needle thereof. The gauge is provided with clamping means adapted to position and retain the edge of the garment to be operated upon at about the ends of its length and to lock the bars of the gauge in position after adjustment, for which purpose arms 13 and 14 conveniently formed as forward extensions of the bars 2 and 6 terminate at their inner ends as plates 15 and 16 parallel with and close to the surface of the sewing machine table.

11a. Jaws or stops 17 and 18 to receive and position the edge of a vest 19, for instance—shown in dot and dash lines in Fig. 1—are pivoted at 17a and 18a to the plates 15 and 16 so that on moving the jaws on their pivots, the edge of the vest 19 can be clamped between them and the underside of the plates 15 and 16.

10 Each clamp is operated separately, the jaws 18 (see Figs. 1 and 3) by means of a pivoted lever 20 connected to the clamp 18 by a rod 21. The one end of the rod 21 is pivoted eccentrically to the lever 20 and its other end is pivoted at 21a to the clamp 18 at a distance from its pivot 18a. The rod 21 may be made adjustable in length in any convenient manner, the arrangement is such that when the lever 20 is in the clamping position—as shown in Fig. 3—it will remain in such position until rocked in an opposite direction.

20 The other clamping means 15, 17 (see Figs. 1 and 2) is similarly arranged but also serves to lock the bars 1—6 in position after adjustment.

25 In order to adjust or space the bars 1—6 apart—the end bar 6 being temporarily fixed as will be presently described—the opposite end bar 1 is made in one with or furnished with a handle 22, and in order to limit the movements of the bars and to provide a means for locking them in position after adjustment, a rod 23 is anchored by its one end at 23a to the top of the bar 6, and then passes freely through an eye 23b carried by the bar 5, and a guide eye 23c carried by the bar 2. Adjustable stops 24 are adapted to be fixed on the rod 23 for limiting the opening and closing movements of the bars 1—5. The bars are 30 locked in position after adjustment by a cam shaped lever 25 adjacent to the eye 23c and through which the rod 23 passes, the said lever 25 being pivoted at its free end to a jointed rod 26 which connects the rocking jaws 17 with a pivoted lever 27 which functions as in the first 35 described clamping means. The rod 26 is articulated at 26a and provided with a universally jointed guide link 26b.

40 The bars 1—6 when in their locked position so as to have no relative motion in respect of each other, are free to slide as a single carriage on the fixed supporting rods 10 under the influence of a tension spring 28 acting between an eye bolt 29a on one of the pivots 8 of the links 7 and the 45 adjacent end frame 12.

45 The intermittent movement of the carriage is controlled under the influence of the spring 28 and the stopping of the sewing machine is effected after the final sewing is effected by mechanism actuated from the stop motion of the sewing machine.

50 In the sewing machine to which this invention is applied the machine is started by momentarily depressing a starting lever 29 and the reciprocating head 11 after a stitching is completed automatically actuates the stop gear of the machine. The motion of the machine is utilized to actuate the intermittent motion of the carriage in any convenient manner. One such way is as follows:

55 The head 11 of the machine is furnished with an arm 11b through which passes a rod 35. Motion is imparted to the rod 35 in one direction by an adjustable stop 35a and in the opposite direction by another adjustable stop 35b carried on the rod 35 and engaging with the arm 11b.

60 The front ends of each bar or finger 1—6, see more particularly Fig. 4, are furnished with a pair of teeth 30, 31 on opposite sides as shown. A lever 32 is pivoted at 32a to a fixed bar 12a connecting the end frames 12 together. The lever

65 32 is furnished with teeth 32b and 32c adapted to alternately engage with the teeth 30 and 31 in the manner of the pallet of an escapement. The tooth 32c is in the form of a spring controlled pivoted pawl made conveniently by pivoting a slotted lever 33 on the pivot 32a furnished on its outer end with a tooth 32c and having its inner end controlled by a compression spring 33a. Stops 33b on the lever 32 are provided to limit the angular movement of the lever 33 with respect to the lever 32. The free end of the lever 32 at 34 is connected to the rod 35, the arrangement being such that as the rod 35 is reciprocated, the teeth 32b and 32c of the pallet 32 will alternately engage with the teeth 30 and 31 and so allow the carriage—under the influence of the spring 28—to be moved intermittently after each stitching is completed.

70 In place of the connecting rod 35, the well known Bowden wire mechanism comprising a flexible inextensible member in combination with a flexible incompressible member may be employed to transmit the motion from the head 11 of the machine to the pallet 32.

75 In order to start the sewing machine by operating the usual starting lever 29 and to keep the latter depressed during the successive stitching operations, the following arrangement is provided. A cranked rod 36, 37 is fixed by its one end 37 to an upstanding plate on the bar or finger 2, and its other end 36 may be guided in a bushing fixed in one of the end frames 12. The rod 36, 37 is carried above and transversely of the bars or fingers. The starting lever 29 of the sewing machine is provided with a dependent 80 blade spring arm 38, provided with a stop or nose 38a adapted to engage beneath the portion 36 of the rod when the lever 29 is depressed by its end 29a and to be released when it reaches the portion 37. It will thus be seen that on depressing the starting lever 29, the nose 38a will engage beneath the portion 36 of the rod and the machine will start stitching. The stitching then proceeds, due to the lever 29 remaining depressed, and as soon as the last buttonhole cycle of the 85 sewing machine to stitch the last buttonhole of the series has been started, the nose 38a will no longer be engaged by the portion 36 but will be opposite the portion 37, and thus be released, allowing the lever 29 to move upwardly and so stop 90 the machine at the completion of that cycle.

95 In operation, the garment, for instance a vest 19 as shown in Fig. 1 is positioned on the table 11a of the sewing machine with its edge engaging within the stops formed by the clamps 17, 18, the lever 20 is then operated to clamp the vest at its edge. The carriage, by means of its handle 22 is then slid on the rods 10 until the bar 6 is engaged by the pallet 32, when the position for the first buttonhole 19a will be immediately beneath the needle bar of the machine. After the stops 24 have been set to fix the spacing of buttonholes required to be sewn, the bars 5—1 are extended by the handle 22 until the number of said bars, corresponding to the number of 100 buttonholes, fill up the allotted space. The lever 27 is then operated to clamp the edge of the vest, and at the same time lock the bars in position by means of the cam lever 25 and rod 23. The machine is then set in operation by momentarily depressing the starting lever 29, the head thereupon moves in sewing down the first side of the buttonhole, the arm 11b engaging the stop 35b of the rod 35 as the head approaches the limit of its movement in that direction at the eye end of 105

the buttonhole, shifting the rod 35 thereby disengaging the tooth 32c from the tooth 31 and causing the tooth 32b to engage the tooth 30, see Fig. 4. The head 11 then moves in sewing down the second side of the buttonhole, the arm 11b engaging the stop 35a as the head approaches the limit of its movement in this direction, thereby shifting the rod 35 at the end of the sewing operation. This movement releases the tooth 32b from the tooth 30, and allows the carriage under the influence of the spring 28 to move until the tooth 31 of the second bar 5 is engaged by the tooth 32c of the pawl 33. As the pawl 33 is capable of slight spring controlled movement on its pivot 32a, after the tooth 32c is disengaged from the tooth 31 (say of the bar 4, see Fig. 4) it cannot re-engage therewith, but is free to assume its normal position ready to engage with the tooth 31 of the next bar 3. As soon as the first buttonhole 19a is completed, the motion of the head 11 connected with the arm 11b, operates the pallet 32 so as to allow the carriage, under the influence of the spring 28 to move until the second bar 5 is engaged by the pallet 32 and thus move the vest 19 into a new position for sewing the second buttonhole 19b.

In Fig. 1 the machine is shown at the start of a stitching operation, the downwardly turned tooth 31 of the bar or finger is engaged by the tooth 32c of the lever 33. As the machine reaches the eye end of the buttonhole, the lever 32 is operated, causing the tooth 32b to engage with the tooth 30 and the tooth 32c to be disengaged from the downwardly turned tooth 31. The tooth 32b engages with the upturned tooth 30 of the bar or finger 4 (see Fig. 4) before the tooth 31 is released from the tooth 32c. As soon as the tooth 32c is clear of the tooth 31, and the tooth 32b is fully engaged with the tooth 30, the lever 33 moves outwardly on its pivot 32a under the influence of the spring 33a into the position shown in Fig. 4. During this time there has been no movement of the carriage. The stitching then proceeds, and when finished the rod 35 is again operated but this time in the opposite direction, causing the tooth 32b to disengage the tooth 30 and allow the carriage to move under the influence of the spring 28, so that the downwardly turned tooth 31 of the next bar or finger 3 is engaged with the tooth 32c thereby moving the lever 33 on its pivot against the action of the spring 33a and the cycle of operations is repeated. Each successive buttonhole is then sewn in like manner until the last buttonhole is completed whereupon the machine is stopped.

The cranked portion of the rod 36, 37 is so arranged that the starting lever 29 is released during the shift of the carriage after sewing the buttonhole 19c, i. e., immediately after the hole 19c is completed, the machine stitching the last hole 19d with the starting lever 29 raised or in the "off" position, the stop motion only coming into action when the machine next comes to the end of a stitching cycle, i. e., after stitching the hole 19d.

The above described construction is applicable to buttonhole sewing machines, and button sewing machines and bar tacking sewing machines in which the stitch frame is reciprocated whilst the garment is held stationary, but it will be understood that by suitably modifying the mechanism, it may be used in conjunction with sewing machines in which the stitch frame is not traversed but the garment is moved.

I declare that what I claim and desire to secure by Letters Patent is:

1. In combination with an automatic buttonhole sewing machine of known type in which the work is held stationary, and the relative movement of the parts to sew about the buttonhole is produced by travel of the stitch frame including the sewing head of the machine, a gauge consisting of a plurality of indicating fingers held movably parallel and mechanism for equally spacing them apart, means for carrying the gauge in a slidable manner transversely in relation to the stitch frame including the sewing head of the sewing machine, clamping means for holding the edge of the garment to be operated upon beneath the needle bar of the machine, and locking the gauge after adjustment, means for automatically sliding the gauge, and with it the garment after each separate stitching is completed, and means carried by the gauge co-acting with the starting and stopping gear of the machine to keep the machine in operation and stop it on completion of the required number of separate stitchings.

2. In combination with an automatic buttonhole sewing machine of known type in which the work is held stationary, and the relative movement of the parts to sew about the buttonhole is produced by travel of the stitch frame including the sewing head of the machine, a gauge consisting of a plurality of indicating fingers held movably parallel by links pivoted together and to the fingers in the manner of lazy tongs, means for adjusting and limiting the spacing apart of the fingers, means for locking the fingers after adjustment, a pair of parallelly arranged rods carried parallel with the front edge of the machine, and on which the gauge is adapted to slide, a spring for controlling the sliding movement of the gauge, a pair of clamps adapted to position and retain the edge of a garment between them and beneath the needle bar of the machine, means for operating each clamp separately, mechanism operated from the head of the machine to release and allow the gauge under the influence of its spring to move after one stitching has been completed into a position for the next stitching, means for keeping the starting lever of the machine in a depressed or starting position during the separate stitchings and releasing it or stopping the machine after the whole of the stitchings have been completed.

3. A machine for spacing and forming a plurality of buttonholes and other separate stitchings in articles of clothing comprising in combination with an automatic buttonhole sewing machine of known type in which the work is held stationary, and the relative movement of the parts to sew about the buttonhole is produced by travel of the stitch frame including the sewing head of the machine, a plurality of indicating fingers, a series of links pivoted together in pairs at the centre of their lengths and at their ends, attaching the end pivots to the fingers to allow the latter to move parallelly with each other, a pair of fixed parallelly arranged guides carrying the fingers transversely in a slidable manner thereon, a frame carrying said guides in parallel relation to the front edge of the sewing machine, a spring for controlling the sliding motion of the connected fingers, a handle for moving the fingers against the action of the spring, a pair of stops and clamps carried by the fingers to position and clamp the edge of a garment beneath the needle bar of the sewing machine, means for separately operating each clamp, a rod fixed at its one end to an end finger and extending transversely above

the fingers, adjustable stops on said rod adapted to co-act with a stop on one of the fingers to limit the separation apart of the fingers, means for locking one of the fingers, other than the one to which the rod is fixed, to the rod to prevent relative movement of the fingers after adjustment, a spring controlled catch adapted to engage the fingers and prevent their movement

along their supporting guides, mechanism for intermittently releasing said catch operable from the head of the sewing machine, means co-operating with the starting lever of the sewing machine to cause said starting lever to keep the sewing machine in operation, and stop it on completion of the last stitching. 5

GEORGE JESSOP.
